UNITED STATES PATENT OFFICE.

HENRY F. HAGER, OF CHICAGO, ILLINOIS.

BED-SPRING FABRIC.

1,161,661.

Specification of Letters Patent. Patented Nov. 23, 1915.

Application filed April 27, 1914. Serial No. 834,639.

To all whom it may concern:

Be it known that I, HENRY F. HAGER, a citizen of the United States, and resident of the city of Chicago, in the county of Cook and State of Illinois, have invented certain new and useful Improvements in Bed-Spring Fabrics, of which the following is a specification.

My present invention relates to bed spring fabrics in general and more particularly to the type of fabric commonly termed "square" or "rectangular" link fabric.

The invention has for one of its objects the provision of a fabric of the character described, the links of which may be economically constructed and assembled.

The cost of bed spring fabrics is estimated by the trade roughly from the number of pounds of wire needed to form the individual and complete fabric and it is an object of this invention to provide a fabric which will require in its formation a minimum weight of wire consistent with the production of an efficient and durable fabric.

A further object of my invention is to provide a fabric which will not lessen in width materially when weight is sustained by the spring.

A further object of the invention is to provide a fabric of the character described, the links of which will not rattle or make other noise when the fabric is in use or when it is being handled in selling.

A still further object of the invention is the provision of a fabric which may be secured in a bed spring frame by a variable number of helical springs of the type ordinarily provided for this purpose without altering the number of longitudinal rows of links and without altering appreciably the form of these links.

Other objects and advantages of the invention will be apparent as the invention is better understood from the following description when considered in connection with the accompanying drawing illustrating a preferred embodiment thereof.

On the drawing, Figure 1 is a partial top plan view of a fabric embodying my invention shown as secured in a bed spring; Fig. 2 is a longitudinal section taken substantially on the line 2-2 of Fig. 1; Fig. 3 is a perspective view of one of the links forming the longitudinal rows in the fabric; Fig. 4 is one of the links forming the transverse rows, and Fig. 5 is a view similar to

Fig. 1 and showing a somewhat modified form of structure.

Referring to the drawing, reference numeral 6 indicates the frame of the spring which is composed of end members 7 and side bars 8 suitably braced at 9, it being understood, however, that the form of frame and the means of securing the fabric therein are immaterial as they form no part of my present invention. The fabric, generally designated at 10, is secured in this frame by a plurality of helical springs 11 each secured at an end 12 in the end members 7. This fabric preferably consists of a plurality of rows of longitudinal or U-shaped links 13 arranged in rows extending longitudinally of the fabric and a plurality of links 14, whose form will be hereinafter described, arranged in rows extending transversely of the fabric and connecting together the longitudinal rows and connecting also the adjacent links 13 of each longitudinal row. The U-shaped links 13 in the present instance consist of a single piece of wire bent to the form shown in Fig. 3 and have a pair of relatively long parallel legs 15 bent at their ends to form hooks or eyes 16 which are engaged, as will be later described more in detail, with the transversely arranged links 14. Each of the latter links consists also of a single piece of wire having a straight central portion 17 and oppositely extending loops 18 and 19 at each end, the loop 18 which is the loop nearer the central portion being disposed in a horizontal plane when the fabric is assembled and the loop 19 which is at the end of the link being in a vertical plane.

When the fabric is assembled the loops 19 at the ends of the links 14 are engaged at the centers 20 of the longitudinal loops, the loops 19 of two adjacent links 14 of the same row engaging each U-shaped link 13 at its center. The hooks or eyes 16 at the ends of the next adjacent U-shaped link are engaged in the two loops 18 of adjacent links 14 which are thus brought together, as will be seen in Fig. 1. Thus the links 14 connect the individual U-shaped links of each longitudinal row and with these U-shaped links form a part of this row, so that when the fabric is secured in the frame by the helical springs 11 the pull of these springs is felt not only by the U-shaped links of the longitudinal rows but by the transversely disposed links 14 through the ends which con-

nect the adjacent links 13 of each row. This holds all of the links in the fabric always under tension and prevents any independent movement of any of the links or other parts 3 of the spring such as would produce rattling or other noise.

The loops 18 serve to maintain the legs of the U-shaped links in substantial parallelism so that the pull on the fabric when the link 10 is secured as shown in full lines in Fig. 1 is felt along substantially straight longitudinal lines as is desirable in this type of fabric and there is no part of this pull which will tend to distort any of the links forming the fabric. This permits the use of wire of relatively light weight to form the units as there is no tendency for the links to separate or become distorted in use.

The edges of the fabric may be formed by 20 the usual band 21, shown in Fig. 1, or it may be given what is generally termed a "straight" edge or wire edge, as shown in Fig. 5. Where a band is used it may be connected to the fabric by using the connecting 25 members 22 each of which is substantially half of a link 14, the free end of this member being bent through, or otherwise fixed, in an eye 23 provided in the band. Where a straight wire edge is desired one leg 24 of 30 the edge row of U-shaped links is made longer than the other leg 25, which last-mentioned leg is a substantial duplicate of one of the legs 15 of the link 13 earlier described. The additional length of the leg 24 compensates for the end of the adjacent link 14 35 which connects the leg 25 with the next adjacent edge U-shaped link and the end of the leg 24 is bent around the center 26 of the next edge link, so that the links at 40 the edge of the fabric are connected in part by an adjacent transversely disposed link 14 and in part by engagement of the leg 24 with the center of the next adjacent link. This provides a substantially straight edge.

Where either form of edge is used there 45 is little tendency of the fabric to contract materially under weight as the pull upon the longitudinal rows falls in substantially straight lines which are maintained at 50 evenly spaced relations by the links 14. The loops 18 prevent any slipping of the eyes or hooks 16 and consequently prevent in large part any possible distortion of the fabric.

The fabric is connected to the helical 55 springs 11 by merely hooking the helical springs through the centers 20 of the links at the end of the fabric at which the end U-shaped links are disposed with their centers at the edge of the fabric, as seen at the left in Fig. 1, and hooking the springs at 60 the other end through the two ends of each link, as seen at the right. The connection of the hooked ends of the links 13 to the loops 18 of the transversely arranged links 14 is substantially a pivotal one and when it

is desired to reduce the cost of the fabric to provide a cheap commercial article a helical spring 27, as shown in dotted lines in Fig. 1, may be arranged midway between two longitudinal rows and engaged at the 70 centers of the end links, as shown also in dotted lines. This may be repeated across the fabric and the helical springs thereby required reduced by one-half at this end of the spring and a similar arrangement may, 75 be resorted to at the other end.

It will be apparent that the transverse links 14, when constructed and connected in the fabric as already described, provide sufficient transverse yielding of the fabric and permit these links to move with a slight pivotal action as the fabric gives in use, so that there is no tendency to bend any of the units or links when weight is placed upon and removed from the spring. Where the 80 transverse links are rigidly connected so that they may not give in this manner they eventually crystallize and break.

It will be obvious that various changes 85 may be made in the form and construction 90 of the links without departing from the spirit and scope of the invention and sacrificing any of its material advantages, the form hereinbefore described being merely a preferred embodiment thereof.

I claim:

1. A fabric for a bed spring comprising a plurality of links arranged longitudinally in rows extending lengthwise of the fabric, and a plurality of duplicated links arranged longitudinally in rows extending across the fabric, said last-mentioned links serving to connect adjacent links of the same row extending lengthwise of the fabric.

2. A fabric for a bed spring comprising a 105 plurality of links arranged longitudinally in rows extending lengthwise of the fabric, and a plurality of duplicated links arranged longitudinally in rows extending across the fabric, said last-mentioned links serving to 110 connect adjacent links of the same row extending lengthwise and themselves forming a part of said row.

3. A fabric for a bed spring comprising a 115 plurality of U-shaped links arranged in rows extending longitudinally of the fabric, and a plurality of transversely disposed links connecting adjacent longitudinal rows of links and connecting also adjacent links of the same longitudinal row.

4. A fabric for a bed spring comprising a plurality of U-shaped links having substantially parallel legs and arranged in rows extending longitudinally of the fabric, and a plurality of links arranged in rows extending transversely of the fabric, said last-mentioned links serving to connect the longitudinal rows of said fabric and to connect also adjacent links of the same longitudinal row.

5. A fabric for a bed spring comprising 130

5 a plurality of **U**-shaped links arranged in rows extending lengthwise of the fabric, and a plurality of links disposed transversely of the fabric and connected at their ends to the looped centers of transversely adjacent **U**-shaped links and between their ends to the hooked ends of longitudinally adjacent **U**-shaped links.

6. A fabric for a bed spring comprising 10 a plurality of **U**-shaped links arranged in rows extending lengthwise of the fabric, and a plurality of transversely disposed connecting links, each of said connecting links being provided with a loop adjacent its ends in 15 which an end of a **U**-shaped link is engaged and provided at its ends with a second loop in which the center of an adjacent **U**-shaped link is engaged.

7. A fabric for a bed spring comprising 20 a plurality of **U**-shaped links arranged in rows extending longitudinally of the fabric, and a plurality of links disposed trans-

versely of the fabric, each of said transversely disposed links being engaged at each end in the center of a link forming a longitudinal row and bent to provide a loop adjacent its end in which is engaged an end of the next adjacent link forming the same longitudinal row. 25

8. A fabric for a bed spring comprising 30 a plurality of **U**-shaped links arranged in rows extending longitudinally of the fabric, and a plurality of links arranged in rows disposed transversely of the fabric, adjacent ends of said last-mentioned links being engaged at the center of a **U**-shaped link and 35 said links being bent adjacent their ends to engage the ends of an adjacent **U**-shaped link.
